UNITED STATES PATENT OFFICE.

WILLIAM W. PILCHARD, OF BETHANY, WEST VIRGINIA, ASSIGNOR OF ONE-HALF TO
CAMPBELL JOBES, OF WHEELING, WEST VIRGINIA.

LOCK-STRIKE.

1,250,650.

Specification of Letters Patent. Patented Dec. 18, 1917.

Application filed August 16, 1917. Serial No. 186,591.

To all whom it may concern:

Be it known that I, WILLIAM W. PILCHARD, a citizen of the United States, residing at Bethany, in the county of Brooke and State of West Virginia, have invented certain new and useful Improvements in Lock-Strikes, of which the following is a specification.

This invention relates to lock strikes and has for its object the provision of means whereby the bolt and latch engaging member may be adjusted to compensate for sagging or shrinking of the door or the door-frame without removing the lock strike from the door jamb. A secondary object of the invention is to provide a device for the stated purpose which may be readily applied to a door jamb and which, when applied, may be adjusted by an unskilled person without detracting from the neat appearance of the door or the door-frame.

The invention is illustrated in the accompanying drawings, in which

Figure 1 is an elevation of a portion of a door jamb with my improved strike applied thereto;

Fig. 2 is a sectional view taken in a plane immediately in rear of the base plate of the lock strike;

Fig. 3 is a longitudinal transverse section of the complete device in position on the door jamb;

Fig. 4 is a perspective view of the face plate or bolt engaging and holding member;

Fig. 5 is a perspective view of the base plate.

In carrying out my invention, I form a recess 1 in the door jamb 2 for the reception of the strike in the usual manner. In the base 40 of the recess 1, I form a central seat 3 and from the ends of said central seat longitudinal grooves 4 extend to the ends of the recess 1. At the ends of said grooves 4, sockets or cavities 5 are provided for a purpose which 45 will presently appear. Extending laterally from the side walls of the seat 3 are recesses or grooves 6 which extend to the side walls of the recess 1 and at the ends of said grooves are sockets or cavities 7 similar to 50 the sockets or cavities 5. The lock strike comprises a base plate 8 adapted to be secured in the recess 1 and a face plate 9 adapted to bear against the outer surface of the base plate and provided with the usual 55 lip or projection 10 against which the latch

may strike as the door is closed. The base plate 8 is of the proper dimensions and form to fit snugly within the recess 1 and at its corners or at other convenient points is provided with openings 11 through which 60 screws or other fastening devices 12 may be inserted into the door jamb to secure the plate in place. The base plate is constructed with a longitudinal slot or opening 13 which is approximately of the same dimensions as the seat 3 formed in the door jamb and at the ends and sides of the base plate, lugs 14 are formed on its rear surface at its edges to enter the grooves 4 and 6 in the door jamb. These lugs and the corresponding 65 grooves should be of such dimensions that the lugs will fit easily but closely within the grooves so that the engagement of the lugs and grooves will aid in retaining the base plate in its proper position. The lugs 70 are perforated and the perforations are internally threaded as will be readily understood upon reference to the drawings. Other lugs 14', the openings through which 75 are unthreaded, are provided between the ends of the slot 13 and the end lugs 14. The face plate 9 is provided with openings or slots 15 for the reception of the ends of the bolts and latch and on its rear side around the edges of said openings or slots are ribs 80 or flanges 16 which are adapted to extend into the seat 3 and are provided with longitudinal slots 17 having beveled walls, as 85 shown most clearly in Figs. 2 and 3. Retaining screws 18 having beveled heads are 90 inserted through the slots 17 to engage the threaded openings in the lugs 14 and thereby 95 secure the face plate upon the base plate, the end screws 18 being longer than the side screws and having their intermediate unthreaded portions passing through the lugs 14' and being thereby held against bending. The beveled heads of the screws by their 100 engagement with the beveled walls of the slots will secure the face plate so that it 105 can not drop away from the base plate or the door jamb but will permit adjustment of the face plate relative to the base plate and the door jamb both longitudinally and transversely. The ends of the screws in extreme positions of the face plate will extend into the sockets 5 and 7 so that a wide range of adjustment will be permitted.

From the foregoing description, taken in connection with the accompanying drawings, 110

it will be readily seen that I have provided a very simple, inexpensive and efficient device whereby the lock strike may be easily adjusted so that, notwithstanding warping or sagging of the door or shrinkage of either the door or the door frame, the end of the bolt and the latch will be permitted to properly engage and be held by the face plate of the lock. The seat 3 in the door jamb and the slot or opening 13 in the base plate will be large enough to accommodate the ends of the latch and the bolt under all conditions and the outside dimensions of the face plate should be such that said seat and opening 13 will be covered notwithstanding the extreme position in which the face plate may be set. As the only tool necessary to effect the adjustment of the device is a screw driver it will be obvious that the services of a skilled workman will not be needed. When the device is in position the appearance of the door is neat and sightly so that the use of the device will be unobjectionable and the adjusting screws by which the face plate is retained in position upon the base plate will

all be hidden, and the strike will differ very little in appearance from the ordinary lock strike now in common use.

Having thus described the invention, what is claimed as new is:

1. A lock strike comprising a base plate, a face plate fitting against the outer surface of the base plate, and means carried by the rear side of the face plate and engaging the rear side of the base plate to secure the plates in a set position, said means being covered by the plates. 30

2. A lock strike comprising a base plate provided with a bolt receiving opening and having threaded lugs on its rear side, a face plate provided with a bolt opening and having outstanding longitudinally slotted ribs on its rear side, and retaining devices inserted through said ribs to permit relative movement of the face plate and engaging the lugs on the base plate to secure the plates together. 40 45

In testimony whereof I affix my signature.

WILLIAM W. PILCHARD.
